Primary Examiner—Nelson C. Holtje*Assistant Examiner*—Jeffrey Asch*Attorney, Agent, or Firm*—Darby & Darby[57] **CLAIM**

The ornamental design for a display rack, as shown and described.

DESCRIPTION

FIG. 1 is a perspective view from the left side of the display rack embodying my new design;

FIG. 2 is a front elevational view thereof;

FIG. 3 is a left side elevational view thereof, the right side elevational view being a mirror image thereof;

FIG. 4 is a rear elevational view thereof;

FIG. 5 is a top plan view thereof;

FIG. 6 is a bottom plan view thereof;

FIG. 7 is a front view of the display rack; and,

FIG. 8 is a left side elevational view thereof.

The broken line showings in FIGS. 7 and 8 are for illustrative purposes only.
